FIG. 1 is a perspective view of a set of earphones and charging case showing my new design;

FIG. 2 is a front elevational view of the earphones;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof;

FIG. 9 is another perspective view thereof;

FIG. 10 is a front elevational view of a charging case of the set of earphones and charging case, shown separately for ease of illustration;

FIG. 11 is a rear elevational view thereof;

FIG. 12 is a left side view thereof;

FIG. 13 is a right side view thereof;

FIG. 14 is a top plan view thereof;

FIG. 15 is a bottom plan view thereof; and,

FIG. 16 is a perspective view thereof.

The broken lines depict environment that forms no part of the claimed design.
